UNITED STATES PATENT OFFICE.

HENRY A. OWEN, OF WHITINSVILLE, MASSACHUSETTS, ASSIGNOR, BY MESNE ASSIGNMENTS, TO DRAPER CORPORATION, OF HOPEDALE, MASSACHUSETTS, A CORPORATION OF MAINE.

FEELER-MOTION FOR LOOMS.

1,291,103.

Specification of Letters Patent. Patented Jan. 14, 1919.

Application filed June 26, 1916. Serial No. 105,795.

To all whom it may concern:

Be it known that I, HENRY A. OWEN, a citizen of the United States, residing at Whitinsville, in the county of Worcester, 5 State of Massachusetts, have invented a certain new and useful Improvement in Feeler-Motions for Looms, of which the following is a specification, reference being had therein to the accompanying drawings.

10 The invention has relation to feeler-motions such as are employed in looms for detecting when the supply of weft contained in a shuttle on the lay of a loom has become depleted to a predetermined extent.

15 The invention comprises a novel disposition and relationship of the feeler-carrier of a feeler-motion of the general class represented by that of U. S. Letters Patent, No. 1,127,086, granted Feb. 2, 1915. Thereby

20 the working of the feeler-member and actuator is rendered more reliable and accurate. Also, the feeler-motion is adapted for application to looms to which the feeler-motion shown in the said Letters Patent is not

25 conveniently applicable. The invention comprises, the various features herein described.

The drawings show illustrative embodiments of the features of the invention.

30 In the drawings,—

Figure 1 is a plan view of portions of a loom with one of the said embodiments applied thereto.

35 Fig. 2 is a front elevation of the parts that are shown in Fig. 1, omitting the shuttle-box and shuttle.

Fig. 3 is a view in section in the plane indicated by line 3, 3, Fig. 2, looking in the direction indicated by the arrows at the 40 ends of such line.

Fig. 4 is a plan view showing a second embodiment of the features of the invention.

Fig. 5 is a plan view of the improved feeler-tip or contact-point, Fig. 6 is a side 45 elevation thereof, Fig. 7 is an elevation of the working end thereof, and Fig. 8 is a view of the stem of the said feeler-tip or contact-point in cross-section on line 8, 8, of Fig. 6.

Fig. 9 shows an alternative means for calling a change.

Fig. 10 is a sectional detail view of the pivotal mounting of the feeler-member.

Having reference to the drawings, and first to the illustrative embodiment that is shown in Figs. 1 and 2,

55 The main features of the feeler-motion of Figs. 1 and 2, as in the case of that shown and described in Letters Patent No. 1,127,086, comprise a laterally displaceable feeler-member 1 furnished with a feeler-tip 2 of a slipping type, an actuator 3 that is combined operatively with the said feeler-member, a carrier 4 for the feeler-member and actuator, arranged to swing around a pivotal mounting 4^a upon a feeler-stand 5, and 60 a controller 6 pivoted at 7 upon the said feeler-stand and adapted to be actuated by the actuator 3, and also arranged to control the latch, catch, or dog 8 of the devices for calling a change in the operation of a loom. 65

70 The general construction shown in Figs. 1 and 2, taken as a whole, is of a later design than that shown in Letters Patent No. 1,127,086, and the specific construction of the parts that have been named varies from 75 that shown and explained in such Letters Patent. In addition, the said general construction includes the features of the present invention, as well as various specific features of invention that have been made the 80 subject of separate application for Letters Patent.

85 As in Letters Patent No. 1,127,086, the feeler-member 1 in Figs. 1 and 2 of the accompanying drawings is the more immediate support and carrier for the actuator 3, and lateral displaceability of the feeler-member is provided for by arranging it to swing in a horizontal plane around a pivot 9 on the feeler-carrier, although these precise characteristics are not in themselves essential to the present invention. Also, by means of a contracting spiral spring 10 the feeler-member is held normally against a stop 11 upon the feeler-carrier 4 in a position such that the actuator will miss the engaging end-piece 6^a of controller 6 if the feeler-carrier 4 is swung forward around its pivot 4^a with the feeler-member in contact with such stop. As in such Letters Patent, 95 100

also, the feeler-carrier normally is held in a rearward position against a fixed stop 23 upon the feeler-stand by the action of a suitable spring (herein designated 24) and the 5 feeler-tip 2 projects rearwardly from the feeler-member in position to enter slots 12 and 13 in the shuttle-box front-plate 14 and the front wall of shuttle 15, respectively, as the lay 16 beats up with the shuttle in the 10 shuttle-box at the feeler-side of the loom, so that the feeler-tip shall receive against its acting extremity the blow or pressure of the shuttle-contents.

The mode of operation, in general, of the 15 feeler-motion of Figs. 1 and 2 resembles that in the case of the feeler-motion shown in Letters Patent No. 1,127,086. Certain differences are indicated hereinafter. Such 20 mode of operation may be briefly stated as follows: As in the said Letters Patent, so long as the weft-carrier within the shuttle continues to hold a sufficient thickness of weft to prevent the extremity of the feeler-tip from slipping lengthwise of the weft-carrier under the effect of the forward blow or pressure against such extremity, the actuator goes forward at one side of the 25 engaging piece 6^a of the controller 6 as the feeler-member and its carrier 4 are driven forward, and consequently misses the said engaging piece. This follows from the fact that when the feeler-tip is thus held from slipping the feeler-member remains in contact with or close to the stop 11 on the 30 feeler-carrier as the feeler-member and feeler-carrier are driven forward by the blow or pressure against the feeler-tip. When the supply of weft within the shuttle becomes so far depleted that it no longer 35 is capable of preventing the feeler-tip from being deflected lengthwise of the weft-carrier by the forward blow applied through the weft-carrier, the resulting turning movement of the feeler-member around its 40 pivotal mounting 9 upon the feeler-carrier, the extent of which is limited by the stop 111 upon the said carrier, and which takes place before the feeler-carrier goes forward, will throw the engaging end of the actuator 45 into line with the engaging end-piece 6^a of the controller, so that in the forward stroke of the feeler-carrier the actuator will engage such end-piece and actuate the controller. Thereby the controller will be turned 50 around its pivot 7, from its normal position defined by a stop 17 upon the feeler-stand, against which the controller is held by the action of a spring 18. Substantially as in the Letters Patent aforesaid, as the controller 55 is thus turned, its extension 6^b will act against the cam-shaped portion 8^a of latch, catch, or dog 8 and turn the latter upon its pivot 8^b carried by the arm 19 mounted on the transversely-extending 60 shaft 20 below breast-beam 21. By this

turning movement of the latch, catch, or dog its shoulder 8^c, Fig. 3, will be placed in the path of movement of a convenient striker 22, usually carried by the weft-hammer, and as a result of the engagement of 75 the forwardly-moving striker with the latch, catch, or dog, the latter and arm 19 will be moved forward, and thereby the predetermined change in the operation of the loom will be called. As the actuator 75 disengages from the engaging piece 6^a of the controller, the spring 10 will turn feeler-member 1 reversely upon its pivot 9 until it brings up against stop 11, and spring 80 18 will return the controller to its normal position against stop 17. As the return movement of the controller causes extension 6^b to clear the cam-shaped portion 8^a of latch, catch, or dog 8, the overbalancing front arm of the latter will cause it to 85 swing clear of the striker 22. As the lay recedes, the feeler-carrier 4 through the action of the contracting spiral spring 24, which is engaged with a short arm 4^b of the feeler-carrier, will be swung rearward 90 against the stop 23 aforesaid upon the feeler-stand, which defines the normal or waiting position of the feeler-carrier.

The stops 11, 111, 17, and 23 are adjustable screw-stops, the stops 11 and 111 being screwed through threaded holes in a piece or lug rising from feeler-carrier 4, and the other two being screwed through threaded holes in lugs forming portions of the feeler-stand 5. Spring 10 is engaged at 100 one end thereof with an adjustable screw-pin 25 occupying a hole in a lug 26 rising from the feeler-carrier, and nuts 29, 29, upon the said screw-pin at opposite sides of said lug serve to adjust it lengthwise to 105 vary the tension of the spring 10. Lock-nuts 11^a, 111^a, 17^a, and 23^a in connection with screw-stops 11, 111, 17 and 23 prevent accidental loss of adjustment of such stops. The tension of spring 24 is regulated by 110 adjustment of the screw 24^a, to which one end of such spring is connected, along a slot 4^c, Fig. 1, in arm 4^b of the feeler-carrier 4. The screw is held at the desired point in the length of such slot by means 115 of a nut 24^b, Fig. 2, upon the stem of such screw below arm 4^b, which nut may be tightened against the underside of such arm so as to clamp the arm between the nut and a washer 24^c on the top of the arm, beneath 120 the head of the screw. These various details in themselves form no part of the present invention.

A feature of the present invention is the 125 construction of the feeler-motion with the point of pivotal support 4^a for feeler-carrier 4 located laterally outward beyond the feeler-member, with the feeler-carrier 4 extending inward from the said point of pivotal support toward the loom, and with the

pivotal mounting 9 for the feeler-member located upon the inward extension of the feeler-carrier. This location of the supporting pivot 4^a, and arrangement of feeler-carrier 4, enable the entire feeler-carrier to be disposed outward beyond the controller if desired, and substantially in line therewith laterally of a loom. In virtue of the pivot 4^a and feeler-carrier being disposed outward beyond the controller, the parts are less crowded in the neighborhood of the shipper-handle, knocking-off devices, etc., and do not take up as much space in the direction from front to rear, as when the 10 pivots of feeler-carrier and controller are adjacent each other, with the controller located parallel with the feeler-carrier, or substantially so, as in Letters Patent No. 1,127,086. The arrangement shown in said 15 Letters Patent is unsuited for employment in conjunction with some combinations and arrangements of shipper-handles, knocking-off devices, and brake-operating handles, as for instance the construction and arrangement 20 shown in the accompanying drawings. In the latter a portion of the shipper-handle is indicated at 30 it working in the slot 31 in the bracket 32 to which feeler-stand 5 is bolted, the said slot having the usual forwardly-offset notch 30^a in which the shipper-handle is detained for the purpose of keeping the driving-power on. At 33 is a knocking-off lever which extends in usual manner transversely in front of the said slot, and at 25 34 is a brake-operating handle of known function, forming in itself no part of this invention, that is pivoted upon said bracket 32 at 34^a alongside a slot 35 through which connecting-rod 36 extends from said brake-operating handle down to a brake-connected lever, the two slots 31 and 35 being quite close together. As will be perceived, my 30 present location and arrangement of parts as aforesaid, avoids the crowding and resulting drawbacks of the earlier construction. Another advantage of the outboard pivotal mounting of the feeler-carrier is the fact that as the feeler-carrier swings forward it does not carry the actuator 3 of the feeler-member into the path in which the shipper-handle moves as it flies outward upon being disengaged from notch 30^a of slot 31. Consequently the shipper-handle will not strike against the actuator, if released at the instant when the feeler-carrier, feeler-member, etc., are forward. This is important in a loom in which, as in Figs. 1 to 3, the arm 19 is furnished with a lug 19^a adapted to engage the knocking-off lever 33 and actuate the latter to release the shipper-handle 30 from its holding notch 30^a when catch, latch or dog 8 is engaged by the striker 22 and the arm thereby swung forward.

Preferably, the pivot 9 by which feeler-member 1 is mounted upon the feeler-carrier

is located slightly rearward with relation to pivotal stud 4^a on which the feeler-carrier is mounted, so that the first portion of the curved path of movement of the actuator 3 is inwardly-inclined toward the position of 70 the engaging piece 6^a of the controller. This makes in favor of certainty of engagement.

The outboard arrangement of the pivotal mounting 4^a of the feeler-carrier permits of the use of a long feeler-carrier. It has the 75 further advantage that the path of movement of the feeling extremity of the feeler-tip is more nearly normal (at right angles) to the incline of the tapering nose of the diminishing mass of weft upon the weft-carrier, than when the feeler-carrier is mounted upon an inwardly-located pivot. Less drag or friction upon the exterior of the mass of weft occurs. The action of the 80 feeler-point is more reliable, also, when working throughout the prolonged stage in which a parallel-sided or approximately parallel-sided, i. e. cylindrical or approximately cylindrical, mass of large diameter is presented to the feeling extremity of the 85 feeler-tip.

I form the feeler-tip 2, as shown in Figs. 5 and 6, with a rather large acting end or extremity which I have hollowed or grooved transversely, as at 2^a, Figs. 6 and 7, so as 90 to render the said end or extremity concave to fit a portion of the convex periphery of a bobbin or shuttle-spindle. The prominent portions 2^b, 2^b, at the top and bottom of the concavity are toothed, as shown in 95 Figs. 1, 5 and 7 to take hold of the turns of weft on the bobbin so as to prevent premature slipping. The enlarged concave surface with the toothed portions above and below the same works well on all classes of work, 100 whether the bobbins that are used are enamelled, shellacked or oiled; and on mule-cops; and even on glazed paper tubes. This form of feeler-tip has proved capable of universal 105 adaptation to all classes of work, rendering 110 it serviceable for use, for instance, in a change-box loom having cop-weft in one shuttle and weft wound on a bobbin in another, with one and the same setting of the 115 feeler devices.

I have found vulcanized fiber an advantageous material for the feeler-tip, and in practice I have made the same in the form of a round rod or pencil having a squared or oblong rear end or head. Preferably I incase the stem-portion of the feeler-tip in a tube or shell 2^c of suitable stiffening and protecting material. I have employed brass. One end of the said tube or shell takes against the laterally outstanding angular 120 portions of the squared or oblong rear end or head, as indicated in Figs. 5, 6 and 8. The tube or shell may simply have a tight fit upon the stem of the feeler-tip, or it may be made secure thereon by driving a tongue, 125 130

2^a, Figs. 5 and 8, of the material of the tube or shell into the stem. The divided clamp 1^x or other means of holding the feeler-tip to the feeler-member engages with the exterior 5 of the tube or shell.

The latch-device for keeping the feeler-carrier and associated parts at rest in a forward inoperative position is shown at 41, Figs. 1 and 2. It consists in a hook that is 10 pivotally mounted by means of a screw 43 upon an upstanding portion of a lug 5^a that projects forward from the outer portion of feeler-stand 5. Normally, this hook merely hangs idly as shown in Figs. 1 and 15 2. When, however, the feeler-devices are not required to act, the hook is swung over on top of the feeler-carrier 4, and after the latter has been swung forward against the stop-cushion 42, Fig. 1, carried by the lug 20 5^a, the engaging portion of the hook is pressed or drops down behind the arm of the feeler-carrier. The resulting engagement of the hook with the feeler-carrier serves to keep the feeler-carrier forward, and the 25 feeler-member and feeler-tip in an idle and inoperative position.

Cushion 42 limits the forward throw of the feeler-carrier as it is driven forward by the impact of the shuttle-contents against 30 the feeler-tip.

The feeler-member 1 of Figs. 1 and 2 is arranged for outward deflection of the feeler tip. The actuator moves normally in a path located laterally outward beyond the engaging piece 6^a of the controller. Fig. 4 shows an embodiment of the invention in which the direction of the deflecting movement is the reverse, *i.e.*, inward, and the actuator moves normally in a path located inward with relation to the said engaging piece. In Fig. 40 4 the pivot, 9^a, by which the feeler-member is mounted upon the feeler-carrier, is located outward beyond the feeler-tip, and the feeler-member arm which carries the feeler-tip extends inward from the said pivot, whereas in Figs. 1 and 2 the corresponding pivot is located inward of the feeler-tip and the supporting arm of the latter projects outward from the pivot. The parts more immediately associated with the feeler-member also are reversed in a lateral direction. This reversal extends to and includes the engaging piece, here designated 61^a, of the controller, here designated 61, the said engaging piece 50 being mounted upon an outward extension of the controller so as to extend inward into close proximity to the normal position and path of the actuator 3. The embodiment shown in Fig. 4 is advantageous for use in 60 connection with weft wound so that the exterior of the base or butt-portion of a wound mass has a pronounced taper toward the head of the weft-carrier, as frequently occurs in mill-practice. With this construc-

tion and arrangement the actuator becomes 65 more completely engaged with the engaging piece of the controller as the two go forward in unison, and hence stays engaged therewith. In the case of the first embodiment of the invention, there occurs a quick 70 disengagement of the two parts as they go forward together.

Referring to Fig. 10, the pivot 9 of the feeler-member is shown therein as a stud having a shoulder 9^b and a screw-threaded 75 lower portion 9^c below such shoulder. The said threaded portion extends through a hole in the feeler-carrier 4. The shoulder rests upon the top surface of the feeler-carrier, and a nut 9^d applied to the threaded portion 80 under the feeler-carrier is screwed up so as to fasten the stud in place. A cotter-pin 9^e inserted into a hole made through the upper end of the stud holds the feeler-member from rising upon the stud. An annular enlargement 9^f of the bore through the feeler-member, at the top of the hub-portion of the feeler-member, constitutes an oil-chamber, thereby providing for adequate lubrication 85 of the pivot.

The character of the change that is arranged to be called in the operation of the loom may vary in practice. Such change may consist in simple stopping of the loom, as provided for in Figs. 1, 2, 3, by means 95 of the lug 19^a with which arm 19 is furnished for engagement with the knocking-off lever 33 to actuate the said lever as the arm is moved forward. In most cases the said lug will be omitted and arm 19 will be 100 made fast upon shaft 20, with which will be combined provisions for bringing about automatic weft-replenishment.

The alternative means for calling a change that is shown in Fig. 9 contains a latch, 105 catch or dog 8^a, hinged by a pivot 81^b to the upper end of an arm 19^c clamped upon the controlling shaft 20, for automatic weft-replenishing instrumentalities. The cam 8^d 110 against which the extension 6^b of the controller acts is located at the under side of the said latch, catch, or dog. In the normal position of the controller the said extension occupies a position in which it is presented under a hollow of the said under side, and consequently the latch, catch or dog occupies a lowered position in which the engaging portion of a striker 22^e, preferably carried by the weft-hammer, passes above the engaging end 8^e of the latch, catch or dog without engaging with such end. Rearward movement of the extension 6^b, occurring in consequence of the actuation of the controller by means of the feeler-member, causes the said extension to act against the cam-portion 115 8^d to raise the latch, catch or dog so as to place its engaging end 8^e thereof in the path of the engaging portion of the striker. 120 125

Thereby engagement of the striker with the latch, catch or dog, and actuation of breast-beam rockshaft 20, are brought about.

What is claimed as the invention is,—

- 5 1. A weft-feeler mechanism comprising a feeler-stand extending outboard with reference to the loom, an outboard pivotal mounting on said feeler-stand, a feeler-carrier mounted thereon, carrying inward of the pivot a laterally-displaceable slipping feeler-member and an actuator made operative by lateral displacement of the feeler-member, and swung around said pivot by impact of the shuttle-contents against the 10 feeler-member, and a controller actuated by said actuator through the swinging movement of the feeler-carrier upon slipping and consequent lateral displacement of the feeler-member in the feeling action.
- 15 2. A weft-feeler mechanism comprising a feeler-stand extending outboard with reference to the loom, an outboard pivotal mounting on said feeler-stand, a feeler-carrier mounted thereon, carrying inward of the pivot a laterally-displaceable slipping feeler-member and an actuator made operative by lateral displacement of the feeler-member, and swung around said pivot by impact of the shuttle-contents against the 20 feeler-member, and a controller mounted upon an inwardly located pivot and adapted to be actuated by said actuator through the slipping and consequent lateral displacement of the feeler-member in the feeling action.
- 25
- 30
- 35

3. A feeler motion for looms comprising in combination a feeler carrier, a side-slipping feeler member pivoted thereon, a lug on the carrier, a stop-screw transversely threaded in said lug to limit the pivotal movement of said member on the carrier, a second lug on said carrier and an adjustable spring connecting the same to said member. 40

4. In a loom feeler motion, a feeler member adapted to call a change by slipping sidewise on the weft and having a toothed contact tip concaved or grooved on an axis substantially parallel with the direction of its slip. 45

5. In a loom feeler motion, a feeler member adapted to call a change by slipping sidewise on the weft and having a contact tip toothed transversely to, and grooved or concaved parallel with the direction of its slip. 50

6. In a loom feeler motion, a feeler member adapted to call a change by slipping sidewise on the weft and having a non-metallic contact tip provided with one or 60 more yarn-penetrating, tooth-like projections on its upper and lower sides and longitudinally grooved between the projections.

In testimony whereof I affix my signature in presence of two witnesses. 65

HENRY A. OWEN.
